G. T. SWASEY

FOUNTAIN PEN

Filed Sept. 3, 1927

Patented Oct. 16, 1928.

1,687,807

UNITED STATES PATENT OFFICE.

GEORGE T. SWASEY, OF RAYMOND, WASHINGTON.

FOUNTAIN PEN.

Application filed September 3, 1927. Serial No. 217,370.

The present invention relates to improvements in fountain pens and has for its principal object to provide a feeder construction for the pen wherein the same will insure the 5 continuous and positive supply of ink from the ink sack or tube to the pen point or nib.

One of the important objects of the present invention is to provide a fountain pen of the above mentioned character wherein 10 an elastic plug is arranged within the mouth of the fountain pen for holding the pen point and feeder in proper position, and which elastic member affords a rest or support for the pen point that will tend to 15 eliminate vibration of the point and reduce the apparent friction, thereby permitting the pen point to move smoothly over the paper when the fountain pen is in use.

A further object of the invention is to provide a fountain pen of the above mentioned character which is simple in construction, inexpensive, strong and durable and further well adapted to the purposes for which it is 20 designed.

Other objects and advantages will become 25 apparent during the course of the following description.

In the accompanying drawing forming part 30 of this application, and in which like numerals indicate like parts throughout the same:

Figure 1 is a view partly in elevation and partly in section of the fountain pen embodying my invention.

Figure 2 is a transverse section taken substantially on the line 2—2 of Figure 1 looking 35 in the direction of the arrows, and

Figure 3 is a similar section taken approximately on the line 3—3 of Figure 1 looking 40 in the direction of the arrows.

In the drawing wherein for the purpose of illustration is shown the preferred embodiment of my invention, the numeral 1 designates generally my improved fountain 45 pen, the same comprising a relatively short tubular casing 2 open at its respective ends, the lower or outer ends thereof being formed with an inwardly directed flange 3 as clearly illustrated in Figure 1.

The opposite end of the tubular casing is 50 internally threaded for the purpose to be hereinafter more fully described.

Adapted for disposition within the lower end of this casing is the elastic plug 4 which 55 is preferably formed of solid rubber and this plug is provided with a central bore

through which extends the feeder 5. This feeder is preferably formed of hard rubber, although any other suitable material may be used such as is commonly employed in connection with feeder constructions now generally in use in connection with fountain pens.

The lower end of this feeder is closed and is beveled as illustrated at 6, while the upper or inner end of the feeder is formed with a longitudinally extending ink receiving well 7. This well terminates at the intermediate portion of the feeder and the closed end of the well is inclined downwardly as illustrated at 8 and the purpose of this construction will also be presently described.

A conventional pen point or nib is shown at 9 and the same extends over the back side of the feeder 5, it being understood of course 75 that the back side of the feeder is of such shape as to conform to the contour of the pen point or nib, as further illustrated in Figure 3 of the drawing. The upper or inner end portion of the pen point also extends into the bore of the elastic plug 4 and due to the elasticity of the plug the same 80 will positively support the pen point in proper position against the back side of the feeder.

The feeder 5 is formed in its back side with an ink receiving channel 10 which is located directly adjacent the ink conveying opening 11 of the pen point 9. The channel further communicates with the ink receiving 90 well 7 of the feeder 5 at the lower extremity of the well, and this is clearly illustrated in Figure 1.

Pressure is applied to the rear or upper face of the elastic plug 4 by means of the 95 ring 12 and the externally threaded gland or sleeve 13, the lower end of which sleeve is threaded into the internally threaded upper end of the relatively short tubular casing 2 in the manner as clearly shown in Figure 1.

The ring 12 as well as the packing gland or sleeve 13 surrounds the upper or inner end portion of the feeder 5 and these elements, namely the ring and the sleeve are spaced from the feeder so as to permit sufficient play on the part of the feeder due to the provision of the elastic plug 4, thus permitting sufficient resiliency to enable the easy handling of the fountain pen when in use.

A conventional ink containing bag or sack 110 formed of rubber, and designated by the numeral 14 has its open end secured to the

upper beaded end of the feeder 5 so that the ink will be supplied to the well 7 from the bag or sack by gravity. This sack or bag is confined within a suitable barrel 15, the open lower end of which is disposed over the upper portion of the sleeve 13, and held in frictional engagement therewith. The lower end of the barrel is externally threaded as at 16 to receive the usual cap (not shown) which cap will enclose the pen point and feeder when the fountain pen is not in use. Also associated with the barrel 15 is the lever 17 which cooperates with a suitable presser bar (not shown) for cooperation with the ink sack or bag 14 in the manner and for the purpose well known in the art, and as this particular feature forms no important part of the present invention, a detailed description thereof is thought unnecessary.

By constructing a feeder in the manner as shown and above described, the ink from the sack will flow continuously and positively into the well by gravity when the pen is held in position for writing. The ink will flow from the well into the channel 10 and will be fed to the pen point also in a positive and continuous manner when the pen is held in a writing position. The inclined lower end of the well will prevent any possibility of the ink clogging up in the well and when the fountain pen is not in use, the ink which remains in the well can flow back into the bag or sack 14 in an obvious manner.

The simplicity of my improved fountain pen enables the parts to be easily and readily assembled, and furthermore the pen will at all times be positive and efficient in its use.

While I have shown the preferred embodiment of my invention, it is to be understood that various changes in the size, shape and arrangement of parts may be resorted to

without departing from the spirit of the invention and the scope of the appended claims.

Having thus described the invention, what I claim as new and desire to secure by Letters Patent is:—

1. In a fountain pen, a tubular casing open at its respective ends, an elastic plug supported in the lower end of the casing, a compressing sleeve having its lower end portion threaded in the upper end of the casing, a barrel having its open lower end supported on said sleeve, a feeder having its upper end portion extending through the elastic plug and the sleeve, a pen point disposed against the top side of the lower end portion of the feeder, the upper end portion of the pen point extending into the elastic plug, and an ink sack within the barrel and attached to the upper end of the feeder. 50 55 60

2. In a fountain pen, a tubular casing open at its respective ends, an elastic plug supported in the lower end of the casing, a compressing sleeve having its lower end portion threaded in the upper end of the casing, a barrel having its open lower end supported on said sleeve, a feeder having its upper end portion extending through the elastic plug and the sleeve, a pen point disposed against the top side of the lower end portion of the feeder, the upper end portion of the pen point extending into the elastic plug, an ink sack within the barrel and attached to the upper end of the feeder, said feeder being formed with an ink receiving well in its upper end, and a channel in the top side thereof directly adjacent the ink conveying passage of the pen point, the channel communicating with the well. 70 75 80

In testimony whereof I affix my signature.

GEORGE T. SWASEY.
